REEL COVERING RING OR SIMILAR ARTICLE

Eugene Martinez, Irvington, and Marvin Kapilow, Rye,
N. Y., assignors, by direct and mesne assignments, to Reelco Inc., Irvington, N.Y., a corporation of New York

Filed Dec. 18, 1961, Ser. No. 67,951

Term of patent 14 years

(Cl. D61—1)

FIG. 1

The broken line showing of a reel within the covering ring in FIGURES 2, 3 and 4 is for illustrative purposes only.

We claim:

The ornamental design for a reel covering ring or similar article, substantially as shown and described.
